UNITED STATES PATENT OFFICE.

WILLIAM KERR EDGAR, OF IOLA, KANSAS, ASSIGNOR OF ONE-FOURTH
TO JAMES W. FRENCH, OF IOLA, KANSAS.

CAR-SEAL.

SPECIFICATION forming part of Letters Patent No. 759,355, dated May 10, 1904.

Application filed May 23, 1903. Serial No. 158,464. (No model.)

To all whom it may concern:

Be it known that I, WILLIAM KERR EDGAR, a citizen of the United States, residing at Iola, in the county of Allen and State of Kansas, have invented certain new and useful Improvements in Car-Seals, of which the following is a specification.

My invention relates to car-seals; and my object is to produce what I term a "universal" car-seal—*i. e.*, one applicable to the freight-car equipment of all railroads and which eliminates all possibility of a car being opened by unauthorized persons without discovery by the inspector at the next station passed.

A further object is to produce a device of this character which can be easily and quickly applied in operative position and which is of simple and cheap construction.

With these objects in view the invention consists in certain novel and peculiar features of construction and organization, as herein-after described and claimed, and in order that it may be fully understood reference is to be had to the accompanying drawings, in which—

Figure 1 is a perspective view of a common form of door-pin equipped with a car-seal embodying my invention. Fig. 2 is a vertical longitudinal section of the car-seal and of the lower portion of said pin. Fig. 3 is a vertical cross-section taken on the line III III of Fig. 2. Fig. 4 is a sectional perspective view of the frangible pocket. Fig. 5 is a detail plan view of the spring-catch.

Referring to the drawings in detail, which show the various parts full size, except Fig. 3, enlarged, 1 designates a pocket constructed of clay, glass, cast-iron, or other material which when broken cannot be quickly and practically mended. This pocket is preferably of oblong rectangular form and at one end is provided with a mouth or opening 2, communicating with the pocket-chamber 3, said mouth and chamber being preferably of oblong rectangular form in cross-section. The chamber 3 is wider than opening 2, so as to form at one edge of the latter the shoulder 4, said shoulder being at the front end of the chamber. At the same edge of opening 2 as

shoulder 4 the chamber 3 is longitudinally 50 extended or deepened, so as to form a shoulder 5 at the base of the chamber and diagonally opposite shoulder 4. The other preferably non-mendable member of the seal is in the form of a cast-iron or other frangible key, 55 consisting of a head or enlargement 6 and a shank 7, having a slightly pointed or rounded end and having its opposite edges notched, so as to produce ratchet-teeth 8 with their beveled sides converging forwardly. The 60 front end of the key is of substantially blunt arrow-head form.

The third member of the car-seal is of spring-wire by preference and substantially J shape in side view. It is made by bending a piece 65 of wire at its middle, as at 9, to form forwardly-diverging arms 10 and then bending said arms 10 back upon themselves, as at 11, to form conjointly a tooth.

Before the time arrives for use the pockets 70 are equipped with the spring-catches, the ends 9 of the same being slipped in openings 2, so that when pressed in sufficiently far they will pass under shoulder 5 and permit the catch to enter the long portion of chamber 3 and 75 drop down behind shoulder 4, the parts being so proportioned that when the catch occupies the position mentioned its tooth shall project above the contiguous edge of opening 2. Being composed of two diverging spring-arms, 80 it is held from rattling around in the pocket and accidental dislocation therefrom by the pressure of said arms against the sides of the pocket, as shown most clearly in Fig. 3.

The pocket equipped with the catch and 85 the key are kept separate until applied to seal a car-door or a warehouse door or window or its equivalent. When such function is required of it in connection with a car where the usual apertured locking-pin, as at 12, is 90 employed, the key is slipped through the aperture 13 and then into the opening 2 of the pocket 1. Pressure is then brought to bear upon the head of the key and the rear end of the pocket, so as to force the former into the 95 latter. In such action the arrow-head of the key-shank overcomes the resistance of the catch-tooth and springs it downward until its

end registers with the foremost notch, when the tooth immediately springs upward into said notch and irrevocably locks the key in the pocket. If the distance between the pin 5 and front end of the pocket exceeds the length of one of the notches 8, the operator presses the key and pocket together until said catch snaps into the next notch or into the third or any subsequent one, it being understood that 10 as each beveled tooth passes it springs catch-tooth 11 downward and that the latter instantly resumes its original position after disengagement with the tooth, so as to be ready to resist opposite movement by said key and pocket. At the instant such opposite movement is applied the catch tilts pivotally against shoulder 4 until its opposite end strikes the under side of shoulder 5, which thus acts as a brace to hold the catch in such position that the 15 strain imposed upon its tooth is largely in the line of its length, the result being it successfully withstands any strain that can be imposed upon it by pulling the key and pocket in opposite directions. It will be seen, therefore, that 20 it is only possible to withdraw the key from the locking-pin by either breaking the former or smashing the pocket. If the key is broken—and it can be broken easily, because it will be 25 preferably constructed of frail gray or brittle 30 Steele iron—it will still be impossible for one, if equipped with another key, to extract the beveled shank of the broken one from the pocket without destroying the latter. On the other hand, if the pocket is destroyed without injuring 35 the key a new pocket is necessary, and as all of the pockets used are serially numbered when they are baked, if of clay, which is the preferred material used in their manufacture, it would be very improbable that an unauthorized 40 person would be able to replace the shattered pocket with an unnumbered one which would pass the inspector.

It will thus be seen that I have produced a car-seal which with a key of sufficient length 45 is applicable to the locking-pins of practically all car equipment and which also possesses the other features of advantage enumerated as desirable in the statement of invention.

I am aware that car-seals have been patented 50 embodying a pocket containing a spring-catch and a key to enter the pocket and engage

the catch; but in such devices the catch is rigidly embedded in the pocket. The pocket which I prefer to employ is first formed of raw clay and afterward baked, the baking requiring a temperature so high that a spring-catch within the pocket would be either melted or lose its temper. My claim involves a construction in which the spring-catch must be fitted into the pocket after the latter is completed and in which, therefore, the catch is not embedded by the solidifying or hardening of the substance of which the pocket is made. 55 60

Having thus described the invention, what I claim as new, and desire to secure by Letters 65 Patent, is—

1. The combination of a pocket having an internal shoulder, a spring-catch fitting snugly but loosely in the pocket and having one end adapted to bear against said shoulder and its 70 opposite end against the front wall of the pocket, and provided at the last-named end with a tooth projecting into the plane of the pocket-mouth, and a key extending into the pocket and having its end therein provided with a head or enlargement engaged and held reliably in the pocket by the tooth of said catch. 75

2. The combination of a pocket of substantially oblong rectangular form in cross-section 80 and provided at its front end with a mouth or entrance-opening, and at its opposite end and diagonally opposite said mouth with an extension which increases the depth of the pocket, a key projecting into the pocket and through 85 said mouth and having a substantially arrow-shaped head therein, and a catch adapted to be inserted into the pocket through its mouth and having one end fitting in said pocket extension and its opposite end bearing against 90 the front wall of the pocket, and provided with a tooth engaging the back of the arrow-head of the key; said catch comprising duplicate portions pressing in opposite directions against the contiguous side walls of the pocket. 95

In testimony whereof I affix my signature in the presence of two witnesses.

WILLIAM KERR EDGAR.
